(57) **CLAIM**

We claim the ornamental design for a washing machine, as shown and described.

DESCRIPTION

FIG. 1 is a front perspective view of a washing machine showing our new design;

FIG. 2 is a front view thereof;

FIG. 3 is a rear view thereof;

FIG. 4 is a left-side view thereof;

FIG. 5 is a right-side view thereof;

FIG. 6 is a top view thereof;

FIG. 7 is a bottom view thereof; and,

FIG. 8 is an enlarged view of the encircled portion in FIG. 1.

The evenly spaced dot-dot broken lines in the figures show portions of the washing machine which form no part of the claimed design.

The dot-dot-dash broken lines encircling portions of the claimed design that are illustrated in enlargements form no part of the claimed design.
